UNITED STATES PATENT OFFICE.

CHARLES P. MACGONIGAL AND JOSEPH F. PUTNAM, OF ROCHESTER, NEW YORK; SAID
PUTNAM ASSIGNOR TO SAID MACGONIGAL.

SWITCH.

Application filed March 15, 1922. Serial No. 543,919.

To all whom it may concern:

Be it known that we, CHARLES P. MACGONIGAL and JOSEPH F. PUTNAM, citizens of the United States, and residents of Rochester, 5 in the county of Monroe and State of New York, have invented certain new and useful Improvements in Switches, of which the following is a specification.

The present invention relates to switches 10 and more particularly to the type in which a switch part is provided movable automatically in one direction and held against movement in such direction by holding means controlled by an electromagnet. An 15 object of this invention is to provide a construction of simple and compact form, which will be inexpensive to manufacture. A further object of the invention is to provide an overload switch or circuit breaker for use in connection with motors and 20 having means by which an overload energized magnet may be prevented from actuating the holding means during the starting of the motor. Still another object of the 25 invention is to provide, in connection with a motor circuit, a switch for controlling said circuit, an overload energized magnet for effecting the opening of the circuit, and means operable, only after the circuit is 30 closed by the switch for preventing the overload energized magnet from actuating the holding means. Another and still further object of the invention is to provide a switch 35 having a part movable automatically to open the switch and also movable to a position while the switch is closed without opening the switch, there being also provided means for holding the switch part against movement to open position and an overload energized magnet for operating said holding 40 means to release the switch part, the freedom of the holding means from the overload energized magnet being secured when said switch part is moved to a certain position 45 while the switch is closed and the motor has reached normal running condition. Still another and further object of the invention is to provide a switch part held by a detent in closed position, this detent 50 being controlled by an overload energized magnet and provision being made whereby the freedom of the detent from the overload energized magnet may be insured when the motor has reached normal running condition. The invention further contemplates 55

an improvement in a switch whereby the latter is held in one position by a detent acted upon by a spring which also acts to move the switch part away from the detent after the switch part is freed by such 60 detent.

To these and the other ends, the invention consists of certain parts and combinations of parts, all of which will be herein-after described: the novel features being 65 pointed out in the appended claims.

In the drawings:

Fig. 1 is a side view of a switch constructed in accordance with this invention:

Fig. 2 is a face view of the switch:

Fig. 3 is a view of the other side of the switch with a part broken away:

Fig. 4 is a fragmentary view showing the switch in closed position where the terminals or contacts are under compression to 75 permit the shunting of the electromagnet:

Fig. 5 is an interior view of the switch showing the switch parts in the positions they occupy during the normal running of the motor:

Fig. 6 is a diagram showing the manner in which the switch, illustrated in Fig. 5, connects with the motor:

Fig. 7 is a diagram of another embodiment wherein the detent is insured by 85 mechanical means of its freedom from the overload energized magnet when the motor has reached normal running condition:

Fig. 8 is an interior view of the embodiment of the switch employed in Fig. 7:

Fig. 9 is a section on the line 9—9, Fig. 8:

Fig. 10 is a fragmentary view showing the switch part directly engaging the detent to insure the freedom of the latter from the overload energized magnet: and

Fig. 11 is a detail view of the overload energized magnet and parts cooperating therewith.

In the embodiment of the invention illustrated in Figs. 4 and 5 and diagrammatically in Fig. 6, 1 indicates the motor and 10 2 the source of energy, the motor being controlled by a switch which in this form embodies two contacts or terminals 3 and 4, one of which may be connected by a conductor 5 to the source of energy 2, while the other of which is connected by a conductor 6 with an overload energized magnet 7 that is in turn connected by a conductor 8, plate 9 and conductor 10 with the motor 11.

1. The contacts or terminals 3 and 4 are preferably made yielding or resilient for the purpose which will be hereinafter described. The terminals 3 and 4 are adapted 5 to be connected by a connecting piece 11, which, in this instance, is formed of conducting material such as sheet copper bent into U shape form and pivoted intermediate the ends at 12 on opposite sides of a flange 10 13 which is secured to and insulated from a switch part or lever 14. The switch part or lever 14 is provided with a slot through 15 which tongues or fingers 15 on the flange 13 are passed, these tongues being bent in opposite directions on the opposite side of the switch part 14 so as to secure said flange to the switch part, insulating material or strips 16 being interposed between the flange and its securing tongues and the switch part 20 so that the flange will be insulated from said switch part.

The switch part or lever 14 is, in this instance, pivoted on a stud 17 secured to an insulating base 18 permitting the switch 25 part to turn about an axis perpendicular to said base. This base also has the contacts 3 and 4 mounted thereon and insulated from each other by an insulating member 18^a, the contact 3 having the conductor 30 5 secured to a binding post 19 which is in electrical connection with the contact 3. Movement of the switch part or lever 14 may be effected by a plunger 20 which is guided in a perforated stud 21 on the base 35 18 and has a rocking connection at 22 with the switch part 14 so as to permit the sliding of the plunger 20 and the swinging or pivoting of the switch part 14.

The switch part 14 has, in this instance, 40 a tendency to move to open the switch and to this end has at one end a lateral projected arm 23 with which one end of a helical spring 24 is connected, the arm having a number of openings 25 so that the 45 end 24^a of the spring may be adjustably connected to the switch arm 14 to increase or decrease the spring tension on said member.

With the end in view of holding the 50 switch part against movement under the action of the spring 24, in this instance, to open the switch, a holding means is provided comprising, in this embodiment, a detent 26 pivoted at 27 and having a nose 55 28 adapted to be projected through an opening or slot 29 in the switch part 14 in order that a shoulder 30 on the detent may engage with the face of the switch part 14 disposed away from the face opposite the 60 pivot of the detent. The detent is normally held toward detaining position and to this end, the spring 24 which acts on the switch part 14 may have its opposite end 31 connected with the detent. This 65 connection is preferably adjustable and may

be obtained by providing the detent with a series of openings 32 in any one of which the end 21 may be fitted.

The detent may be controlled manually and to this end it has an arm 33 extending from the pivot 27 in a direction opposite from that from which the main portion of the detent extends. This arm of the detent has a laterally deflected portion 34 to which a finger piece 35 is rigidly secured, this finger piece projecting to one side of the base 18 preferably through an opening 36 in the cover member 37 which fits over the parts on the base and is held thereover by a screw 38. The electromagnet has its coil surrounding, in this instance, one arm 70 75 of a U shape laminated pole piece 39 to the other arm of which the detent is pivoted at 27, the arm on which the coil is arranged being situated beneath the arm 33 of the detent 26 so that said arm acts as an armature for the electromagnet.

When the switch is closed in starting the motor, the starting current, if no means were provided for overcoming the effect thereof, would energize the electromagnet sufficiently to attract the arm 33 and draw the detent 26 to a position where if the manual pressure were relieved from the plunger 20 the spring 24 would shift the switch part 14 and open the switch. With the end in view of insuring the freedom of the detent from the overload energized magnet when the motor has reached normal running condition, suitable means is employed 90 95 which is brought into effect only after and while the circuit is closed by the switch.

In the embodiment shown in Fig. 6 this means is electrical and comprises a shunting means for the overload energized magnet coil 7. In this instance, the shunting is effected by providing a post or contact 40 and making the terminals 3 and 4 resilient or yieldable so that while the connector 11 connects the contacts 3 and 4, the flange 13, which is in electrical connection with said connector 11, may engage the contact 40 and thus establish a shunt circuit from the connecting plate 9 by way of conductor 41 to the contact 40. It will thus be seen that the switch has a switch part 14 movable to a position while the switch is closed by the connector connecting the contacts 3 and 4 without opening the switch, this switch part bringing into effect a means which insures the freedom of the holding means or detent from the overload energized magnet when the motor has reached normal running condition.

In the embodiment of the invention illustrated in Fig. 8 and diagrammatically in Fig. 7, the means for insuring the freedom of the holding means from the overload energized magnet when the motor has reached 125 130 normal running condition is mechanical.

Instead of a shunt circuit for the overload energized magnet, the holding means is positively free from the overload energized magnet when the switch part 14^A is moved to a 5 certain position, while the switch is closed, without opening the switch.

This mechanical means, in this instance, comprises a bevelled face or projection 42 formed on the detent 26 and adapted to be 10 engaged by one wall of the slot or opening 29 in the switch part 14^A after the switch part has moved to close the switch and the contacts thereafter yield. The normal position of the switch is shown in Fig 8 where 15 the cooperation between the switch part 14^A and the detent 26 is shown. The other parts of this embodiment of the invention are the same as like illustrated parts in the embodiment illustrated diagrammatically in 20 Fig. 5.

From the foregoing it will be seen that there has been provided a combined switch and overload circuit breaker in which a switch part is movable to a position, while 25 the switch is closed, without opening the switch for the purpose of insuring the freedom of the holding means for the switch part from an overload energized magnet when the motor has reached normal running 30 condition. This switch part is manually operated in one direction and automatically moved in the other direction by a spring which also acts on a detent forming the holding means for said switch part. The detent 35 has an arm acting as an armature for an overload energized magnet and provided with a laterally turned end on which a finger piece is mounted through which the detent may be manually controlled from the exterior of the cover of the switch. Certain 40 features of the switch are adapted for switch of other types, as for instance, the single spring which acts on the detent and the movable switch part held by the detent.

45 What we claim as our invention and desire to secure by Letters Patent is:—

1. In combination with a switch having a switch part with two positions in which it may lie while the switch is closed, one of 50 said positions being farther away from the extreme open position than the other, means for holding the switch part in the closed position nearer the extreme open position, said means being constructed to permit the 55 switch part to be moved freely toward the closed position farthest from the extreme open position, means in which energy is stored when the switch part is moved away from the extreme open position, said means 60 tending to hold the switch part away from the closed position farthest from the extreme open position, an overload energized magnet for operating the holding means to permit the switch part to move to open the 65 switch under the action of the means in

which energy has been stored, and means brought into effect upon the movement of the switch part to the closed position farthest removed for insuring the freedom of the holding means from the overload energized 70 magnet, said means having provision for causing it to become inoperative when the switch part is moved from the farthest closed position to the closed position nearer the open position under the action of the 75 means in which energy has been stored, so that the holding means can hold the switch part until the latter is released by the overload energized magnet.

2. In combination with a switch having 80 a switch part with two positions in which it may lie while the switch is closed, one of said positions being farther away from the switch part than the other, means for holding the switch part in the closed position 85 nearer the extreme open position, said means being constructed to permit the switch part to move freely toward the closed position farthest from the extreme open position, means in which energy is stored when the 90 switch part is moved away from the extreme open position, said means tending to hold the switch part away from the open position farthest from the extreme open position, an overload energized magnet for 95 operating the holding means to permit the switch part to move to open the switch under the means in which energy has been stored, and shunting means for the overload energized-magnet brought into operation when the switch part is moved to the farthest closed position and thrown out of operation when the switch part is moved toward the closed position nearer the open position by 100 the means in which energy is stored. 105

3. The combination with a switch having a pair of yielding contacts and a switch part movable for connecting said contacts, means for moving said switch part for opening the switch, and means for holding the 110 switch part against movement to open the switch, and an overload energized magnet for operating said holding means to release the switch part, of means, brought into effect upon movement of the switch part, to 115 cause the yielding of the contacts for insuring the freedom of the holding means from the overload energized magnet.

4. The combination with a switch having a switch part movable, while the switch is closed, without opening the switch, and a detent for holding said switch part against movement to open the switch of a single spring acting on the switch part and the detent to give the switch part a tendency to move to open the switch and to hold the detent in detaining position, an overload energized magnet for operating said detent against the action of the spring to release 125 the switch part, and means, brought into 130

- effect upon the movement of the switch part, while the switch is closed, for insuring the freedom of the detent from the overload energized magnet.
5. The combination with a switch having a pivotally mounted switch part movable, while the switch is closed, without opening the switch, and a pivotally mounted detent for holding said switch part against movement to open position of a single spring connecting the detent and the pivotally mounted switch part and acting to move the switch part to open the switch and the detent to hold the latter in detaining position,
- 10 15 an overload energized magnet for operating said detent to release said switch part, and means, brought into effect upon the movement of the switch part, while the switch is closed, for insuring the freedom of the detent from the overload energized magnet.
- 20 25 6. The combination with a switch having a pair of yielding contacts, a switch part operable to connect said contacts, means for moving said switch part to break the connection between the contacts, means for holding the switch part in a position where it will effect the connection between the contacts, and an overload energized magnet for operating said holding means to release the switch part in order to permit the opening 30 of the switch, of shunting means for the overload magnet, brought into effect when the switch part is moved while connecting the contacts, to effect the yielding of the contacts.
7. The combination with a switch having a pair of yielding contacts, a pivotally mounted switch part arranged to connect said contacts, means for moving said switch part to open the switch, means for holding 40 said switch part against movement to open the switch, and an overload energized magnet for operating said holding means to release the switch part, of means, brought into effect upon the movement of the switch part 45 and the yielding of the contacts, for insuring the freedom of the holding means from the overload energized magnet.

CHARLES P. MACGONIGAL.
JOSEPH F. PUTNAM.
